FILM CLEANING APPARATUS

Filed Feb. 7, 1921

UNITED STATES PATENT OFFICE.

MAXWELL COHEN, OF BROOKLYN, NEW YORK, ASSIGNOR TO AMERICAN FILM
CLEANING MACHINE COMPANY, OF BROOKLYN, NEW YORK, A COPARTNER-
SHIP COMPOSED OF MAXWELL COHEN, HENRY LEVY, AND MAXWELL
WEINBERG.

FILM-CLEANING APPARATUS.

Application filed February 7, 1921. Serial No. 443,073.

To all whom it may concern:

Be it known that I, MAXWELL COHEN, a citizen of the United States, and a resident of the city of New York, borough of Brooklyn, in the county of Kings and State of New York, have invented a new and Improved Film-Cleaning Apparatus, of which the following is a full, clear, and exact description.

10 This invention relates to an apparatus for cleaning films and particularly for cleaning moving picture films.

The object in view is to provide an apparatus which will clean both sides of a moving picture film in an efficient manner without injuring the film in any way and at a minimum cost.

20 Another object in view is to provide an apparatus which will gently wash the sensitized side of the film and will polish the opposite side so as to produce a thorough cleaning action thereon.

A still further object of the invention is to provide an apparatus formed with means 25 for thoroughly washing with a general washing action the sensitized side of a moving picture film and then polishing the unsensitized side of the film.

In the accompanying drawing—

30 Figure 1 is a longitudinal vertical section through Figure 2 on line 1—1.

Figure 2 is a top plan view of a film cleaning apparatus disclosing an embodiment of the invention, the cover being removed.

35 Referring to the accompanying drawing by numerals, 1 indicates a container having a cover 2 hinged thereto in any desired manner. The container 2 is preferably provided with one or more lugs 3 so that when the 40 cover 2 is hinged to an open position it may rest on these lugs in a convenient manner. Preferably, a bracket 4 is connected to the container 1 or it could be made independent and fixed in position. The bracket 4 carries 45 certain members for operating on the film as hereinafter fully described, said operation taking place after the film has passed through the container 1.

As indicated in Figure 1 the cover 2 is 50 provided with openings 5 and 6 registering with openings 7 and 8 so as to provide entrance and exit openings for the film 9. The cover 2, in the openings 5 and 6, carries

guiding rollers 10 and 11 which co-act with guiding rollers 12 and 13 in openings 7 and 8. As the film 9 passes through rollers 10 and 12 it moves over a sprocket or feeding roller 14 of the usual type used in moving picture films. The roller or sprocket 14 is connected with a shaft 15 which in turn is rigidly secured to a gear wheel 24. The shaft 15 is journaled in any suitable manner in the container 1 while a gear wheel 24 is arranged in the compartment 17 which is separated by a partition wall 18 and a compartment 19. The compartment 19 carries a cleaning solution which may be of various kinds according to the desire of the operator but preferably a chemical is used which will provide a quick and thorough cleaning of 70 the film without injuring the sensitive coating of the body of the film. Carbon-tetrachloride has been found to be very desirable for cleaning when using the present apparatus as it will produce the desired cleaning 75 action and will quickly evaporate off of the film after the film has left the container. The film 9 extends from roller 14 in a loop 20 to a sprocket or roller 21 which pulls the film and forces the same toward the rollers 11 and 13. A clamping roller 22 is mounted to hold the film 9 against the roller 14, said clamping roller being of the usual type of rollers now in common use whereby it will not injure in any way the sensitive matter on 85 a film while holding the teeth of the sprocket 14 in proper engagement with the film. The roller 22 is rotatably mounted on a pivotally mounted support 23 which support is provided with a squared section 24 against 90 which the spring 25 presses, said spring being rigidly clamped to a suitable supporting lug 26 by a set screw or other suitable means.

When the parts are in the position shown in Figure 1 the spring acts to hold the support 23 and roller 22 in operative position. When it is desired to remove the film 9 from the roller or sprocket 14 the handle 27 is pulled to the left in Figure 1 until the spring 25 engages the support 23 100 at point 28. This will cause the roller 22 to be swung away from the roller or sprocket 24 and be held in a new position by the spring 25. It will thus be seen that the spring 25 holds the roller both in an operative and also in an inoperative position.

2

The gear wheel 24 is arranged to mesh with the gear wheel 29, which gear wheel is an idler though intended to transmit power from the master gear 30 to the gear wheel 24. Preferably, the gear wheels 30 and 24 are of the same size so that they will operate at the same speed. A second idler 31 meshes with the master gear 30 and also with a gear 32 rigidly secured to shaft 33' 10 to which the roller or sprocket wheel 34 is rigidly secured. Gear wheels 24, 30 and 32 are of the same size so that they all rotate at the same speed whereby the film is moved out of the container at the same speed that it is moved into the container. A gear wheel 30 is keyed to the shaft 35 to which the pulley 36 is also keyed. This shaft, however, is keyed to these two members and also to the hub 37 of the scrubbing member 38 in such a manner that it may be slid or moved longitudinally by a pull or push on the thumb member 39. For instance, whenever any of the felt scrubbing members 40 needs renewing, thumb member 39 is pulled until the shaft 35 has been disengaged from the hub 37 and then said hub with its scrubbing members is removed and a new one substituted and the shaft 35 again moved back to the position shown in Figure 2. The scrubbing members 40 may be of any desired material, as for instance, felt and is adapted to wipe against the sensitized side of the film as the loop engages the roller 41 the movement of member 40 being in an opposite direction to the movement of the film. This roller is an ordinary smooth roller rotatably supported on a shaft 42 and is provided with a flange at each end for guiding the film. The felt scrubbing members 40 are, of course, saturated with the liquid 43 and rubs gently against the sensitized side of the film and presses the film against the roller 41. During this action the film would be pulled toward the sprocket or roller 21 and, consequently, there will be a rubbing action which action will thoroughly clean the sensitized side of the film without injury as the contact of the felt members 40 is very slight. Roller 21 is provided with a clamping roller 44 similar to roller 22 and is supported by suitable supports 45, said supports and associated parts being identical with the support of roller 22 but acting in the opposite direction.

After the film leaves the roller 21 it passes between squeezing rollers 46 and 47 which may be made of any suitable material as for instance, soft rubber. If desired, the roller 47 could be made of some hard substance as metal or roller 46 could be made of rubber or other soft material. The object of providing these rollers is to squeeze excess liquid from the film before it passes out of the container 1. After it passes out

of the container 1 it moves in between the rollers 48 and 49 and from thence between other rollers 50 and 51 similar to rollers 48 and 49. The rollers 49 and 51 are formed from felt or other cleaning and polishing material which cleans and polishes the back or rear face of the film while the front face carrying the sensitized material passes beneath the recessed portions 52 of rollers 48 and 50 without contacting with these rollers though the edges of the film carrying the apertures remains in engagement with these rollers. The rollers 49 and 51 rotate at a speed whereby their peripheral speed will be greater than the speed of movement of the film. This arrangement causes the rollers to produce a friction against the film which will not only clean the film but also generate a certain amount of heat which heat helps to quickly drive off any remaining particles of the washing solution 43.

As shown in Figure 2 rollers 49 and 51 are secured to driving shafts 53 and 54, which shafts carry pulleys 55 and 56 for accommodating the belt 57. A second pulley 58 is rigidly secured to shaft 53 for accommodating the belt 59 which belt also passes over a pulley 60 driven by shaft 33'. Pulley 36 accommodates the belt 61 which belt receives power from any suitable source and as it rotates the various gears 24, 29, 30, 31 and 32 are rotated. As the gear 32 rotates it drives shaft 33' and, consequently, power is transmitted through the belts 59 and 57 to the cleaning rollers 49 and 51. The rollers 48 and 50 are idlers and act merely to hold the film in position against rollers 49 and 50.

In operation, after the film has been properly fitted into the apparatus as shown in Figure 1, power is applied to the belt 61 and the film 9 will be automatically moved into the apparatus, cleaned and then moved out so that when it leaves the rollers 50 and 51 it will be clean on both sides and sufficiently dry for winding on an ordinary reel. The cleaning operation may be carried on at a comparatively high speed so that a given length of film may be cleaned in a minimum time and at a minimum cost without danger of injuring the same.

What I claim is:—

1. In a film cleaning apparatus, a tank adapted to contain a cleaning liquid, a revoluble scrubber mounted in the tank and having spaced flexible scrubbing strips, feeding devices in the tank at opposite sides of the scrubber, said feeding devices themselves feeding the film through the tank in loop formation, with the loop depending into the liquid below the scrubber, and a smooth roller below one of the feeding devices and against which the film is pressed by the flexible scrubbing strips of the scrubber.

2. A cleaning apparatus for moving pic-

- ture films, comprising a tank adapted to contain a cleaning liquid, a revoluble scrubbing member mounted in the tank and having a plurality of felt strips, means for 5 moving the film through the tank, said means itself causing the film to form a loop depending into the liquid below the scrubbing member, a smooth roller mounted in the tank adjacent one end thereof and upon 10 which the film is pressed by the felt strips of the scrubbing member to scrub the film as it passes through the tank, a pair of squeezing rollers for squeezing the film as it passes from the tank, and drying means 15 exterior of the tank for drying and polishing the unsensitized side of the film.
3. A film cleaning apparatus comprising a tank adapted to receive a cleaning fluid which readily evaporates when finely divided, means for passing a film through said tank, said means causing the film to assume a looped formation in the tank with the loop submerged in said fluid, a smooth and
- flanged roller arranged adjacent said film while in said tank, a movable scrubbing member of felt adapted to engage the opposite side of said film to that engaging the flanged roller for scrubbing the same, said scrubbing member pressing the film against said flanged roller, and means arranged exteriorly of the tank for cleaning the opposite side of said film to that engaged by said scrubbing member. 25
4. A film cleaning apparatus, comprising a tank adapted to contain a cleaning liquid, 30 means for feeding a film through the tank, means in the tank for cleaning the front sensitized side of the film, and means outside of the tank for cleaning and polishing the rear side of the film, said means consisting of two pairs of rollers between which the film passes, the upper rollers being recessed to prevent injury to the sensitized portion of the film. 35 40

MAXWELL COHEN.
